UNITED STATES PATENT OFFICE

ROY EARL MILLER, OF POTTSVILLE, PENNSYLVANIA

MERRY-GO-ROUND

Application filed February 5, 1930. Serial No. 426,088.

My present invention has reference to an amusement device for children, and is designed to afford both pleasure and healthy exercise for the users thereof.

5 A further object is the provision of an amusement device in the nature of a merry-go-round in which a number of children occupy seats and manipulate levers for turning wheels to cause the device to travel in a circular direction.

10 A still further object is the provision of an amusement device for this purpose that can be easily manipulated and in which friction between the several parts constituting the

15 same is reduced to a minimum.

To the attainment of the foregoing and other objects which will present themselves as the nature of the invention is better understood, the improvement also resides in certain other novel features of construction, combination and operative association of parts hereinafter set forth and specifically pointed out in the appended claims.

In the drawings:

25 Figure 1 is a top plan view of the improvement.

Figure 2 is a side elevation thereof.

Figure 3 is a detail elevation with parts in section to illustrate the coengagement of the 30 pawl of the lever with the ratchet teeth on one of the wheels.

Figure 4 is a sectional view approximately on the line 4—4 of Figure 3.

Figure 5 is a sectional view approximately 35 on the line 5—5 of Figure 2.

Figure 6 is a sectional view approximately on the line 6—6 of Figure 2.

The improvement essentially comprises a 40 circular track 1 which is preferably in the nature of a metal member that is U-shaped in cross section. The track 1 is suitably reinforced and the inner circumferential edge thereof has fixedly secured thereto right angularly arranged plates 2. These plates are 45 in the nature of a cross-shaped member, and the central portion thereof has fixedly secured thereto a post 3. The post is effectively supported by suitable braces 4.

The post is in the nature of a pivot member 50 as the same supports upon the upper and re-

duced end thereof right-angularly arranged arms 5, respectively. The arms are preferably in the nature of metal plates and each of the arms, adjacent to its outer end has fixedly supported thereon a back rest 6. Below the back rest, and at the opposite side or edge of the said arms there is fixedly supported foot rests 7. The foot rests are sustained below the arms by brace members 8 which are fixedly secured to the arms and also to the plates 60 that comprise the foot rests.

Fixed on the lower face of each arm 5 there is a brace rod 9. Each brace rod is directed toward and terminates beneath the outer end of each of the arms 5 and beneath each of the foot rests 7. The lower and straight ends 10 of the rods 9 are outwardly directed and provide axles. These axles are threaded. Arranged on the axles, and held thereto by suitable nuts there are the straight ends of 70 angle brace members 11 which are fixedly secured beneath the respective foot rests 7, and are disposed below the brace members 8. The traction wheels are indicated broadly by the numerals 12. Each of the traction wheels has a rubber tread 13. The body 14 of each traction wheel is made up of two similar parts or sections, each of which being in the nature of discs and have their outer ends rounded or concaved to receive 80 the treads 13 therein. The central or body portion of each of the discs 14 is bulged outwardly, as at 15, and the said bulged portions are provided with central openings through which pass the axles 10. There is 85 screwed on the axle flanged members 16, the said members and the flanges thereof holding thereon anti-frictional balls 17 which are in contact with the inner faces of the bulged portions 15 of the wheel body 14. Suitable 90 nuts 18 hold the members 16 properly positioned on the axle.

The nuts which hold the brace members 11 in position are indicated for distinction by the numeral 19. Arranged around the outer face of each of the axles 10 there is the inwardly directed hub portion 20 of a ratchet wheel 21. Bolts 22, engaged by suitable nuts 23, pass through the sections comprising the wheel body 14 and through the 100

ratchet wheels. These bolts not only hold the ratchet wheel on the wheel but hold the wheel sections assembled.

Screwed on each axle 10, and contacting 5 with the inner face of the inner brace member 11 there is a flanged bearing sleeve 24 held in place by a suitable nut 25. On this bearing there is journaled the lower end of a plate 26. Each plate carries a pivoted dog 10 27 to engage with the respective ratchet wheels 21. Pivots secured to the upper end of each of the plates 26 there is a link 28 and these links in turn are pivotally secured, as at 29, to the lower end of an operating lever 30. Each operating lever passes through a slot 31 in the foot rest 7 and is pivoted therebelow, as indicated by the numeral 30'. The upper end of each of the levers 30 is provided with a laterally 15 extending operating handle 32 and the same is disposed in convenient proximity to the occupant of the seat.

A child occupies each of the seats that is afforded between the back rests 6 and the arms 5. The feet of the child rest upon the platform. The handle 32 is in a convenient position to be grasped by the child and by reciprocating the said handle it will be apparent that the lever 30 will cause the dog 20 27 to turn the ratchet wheel 21 and likewise turn the traction wheels 12 so that the device may be propelled in a circular direction around the track. The construction of the improvement is essential and the advantages 25 thereof will, it is thought, be apparent without further detailed description. Obviously I do not wish to be restricted to the details herein set forth and, therefore, hold myself entitled to make such changes therefrom as 30 fairly fall within the scope of what I claim.

As disclosed by the drawings I preferably employ brace elements 33 between the axle 10 and the outer ends of the arms 5 and also as disclosed by the drawings the track is 45 constructed of sections and the post 3, the braces and arms 5 are removably connected so that the device, when not required for use may have its parts separated and packed to afford a small package for storage or 50 shipment.

Having described the invention, I claim:

1. A child's toy comprising a circular track, a central post arising therefrom, centrally intersecting connected arms journaled 55 on the post, back rests on the outer ends of the arms, a foot rest supported from the arms below each back rest, angle rods fixedly secured to the arms and extending below each foot rest and having a straight end affording an 60 axle, brace means between the axle and the foot rest, a wheel journaled on each axle, and engaging the track, a ratchet wheel fixed on the side of each wheel, a plate journaled on each axle, a pivoted dog on each plate to engage with the ratchet wheel, and an operat-

ing lever pivotally secured to each foot rest and having a link connection with the plate.

2. A child's toy comprising a flat circular track, a post arising centrally therefrom, centrally intersecting arms centrally journaled 70 on the post, back rests on the outer ends of the arms, depending brace members on the arms, a foot rest supported by each brace member, angle brace members secured to the arms and directed below the foot rests and 75 having straight-threaded ends for providing axles, brace means between the axles, the foot rests and the arms, a track engaging wheel journaled on each shaft and whose body portion comprises two discs which have their 80 outer edges rounded to receive a rubber tread therebetween and which have their central portions bulged outwardly and through which central portion the axle passes, anti-frictional means between the axles and the 85 said central portions of the wheels, a ratchet wheel having a hub portion contacting one of the members of each wheel, means securing the ratchet wheel to the track engaging wheel and for holding the sections of the 90 track engaging wheel connected, a plate swingably mounted on each axle, a dog pivoted to the plate and engaging with the ratchet wheel, a link pivotally secured to the plate, a lever pivotally supported on each foot rest 95 and to which the link is pivotally secured and each of said levers having an operating handle.

In testimony whereof I affix my signature.

ROY EARL MILLER.
